Des. 759

Hermann E. Wesche, of Philadelphia, Pa.

Assignor to

Robert Wood, of Philadelphia aforesaid
Letters Patent No 759 Dated Feb 5th 1856.

The schedule referred to in these Letters Patent and making part of the same

To all whom it may concern:

Be it known that I, Hermann E. Wesche, of the
City of Philadelphia, in the County of Philadelphia, and State of Pennsylvania, have invented
or produced a new and original design for a gate, and I do hereby declare that the aforesaid
drawing is a correct and faithful representation of the design, at a small scale, to be
used and to form a pattern for gates for Cemetery and other railings, As seen on the
drawing it consists of a frame fashioned at the top by segments of Circles and in the
middle by a full circle containing an emblem, the all seeing eye, this circle is sur-

rounded by ornamental foliage and flowers thus forming the top of the gate, the inside of the
frame is filled by a plate on which a name is to be put, ornamental foliage, a festoon of
flowers and a morning child, -

I claim it as represented on the drawing, for a gate for
Cemetery enclosures.
